CLAIM

The ornamental design for the medical device for the injection of fluid medicaments, as shown and described.

DESCRIPTION

FIG. 1 is a right side view of the medical device for the injection of fluid medicaments of our new design, the left side view being a mirror image thereof;

FIG. 2 is a right side view of our new design, with an end cap removed, the portion of the device shown in dashed lines forming no part of the claimed design;

FIG. 3 is a front view of our new design;

FIG. 4 is the rear view of our new design;

FIG. 5 is a perspective view of our new design;

FIG. 6 is a top view of our new design; and,

FIG. 7 is a bottom view of our new design.
